UNITED STATES PATENT OFFICE.

RUTH WILMOT, OF NEW YORK, N. Y., ASSIGNOR TO R. H. MACY & CO., INC., OF NEW YORK, N. Y., A CORPORATION OF NEW YORK.

DESIGN FOR BOX-WRAPPING PAPER.

Application filed August 8, 1927. Serial No. 23,018. Term of patent 3½ years.

To all whom it may concern:

Be it known that I, RUTH WILMOT, a citizen of the United States, residing at New York city, in the county of New York and State of New York, have invented a new, original, and ornamental Design for Box Wrapping Paper, of which the following is a specification, reference being had to the accompanying drawing, forming part thereof.

The figure is a plan view of a piece of wrapping paper showing the design, a complete repeat thereof being included between the dotted lines marked A—A, the same being repeated throughout the extent of the piece of paper.

I claim:

The ornamental design for a box wrapping paper, as shown and described.

RUTH WILMOT.
